(57) **CLAIM**

The ornamental design for a waterfowl decoy head, as shown and described.

DESCRIPTION

FIG. 1 is a front perspective view of the waterfowl decoy head showing my new design in use;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines depict environment and are included for the purpose of illustrating only and form no part of the claimed design.
